SPARKING PLUG

Anton Gazda, London, England

Application March 7, 1938, Serial No. 194,471
In Great Britain May 3, 1937

4 Claims. (Cl. 123—169)

Frequently it is the case, that the sparking plugs of internal combustion engines get out of order owing to excessive heating, for instance if the insulator, enclosing the concentrically placed electrode, cracks which may be dangerous particularly in the case of flying machine engines.

In order to prevent excessive heating of the sparking plugs it has been proposed heretofore to provide a hollow central electrode which 10 wholly or in part is charged with a heat absorbing cooling medium. Further it has been proposed to make hollow the metallic body of the plug and charge the same with a cooling medium.

The present invention relates to improvements 15 in sparking plugs of the kind in which the central electrode is surrounded by an insulator and cooled by a heat absorbing cooling medium and its essential feature consists in that that the insulator surrounding the central electrode is made hollow and charged with the heat absorbing cooling 20 medium.

One mode of carrying out the present invention is illustrated by way of example in sectional elevation in the accompanying drawing.

The sparking plug, shown in axial longitudinal section, is provided with a central electrode *a*, which is enclosed in an insulator *b* for instance of porcelain, secured in known manner by a nut *c* to its seat in the plug-casing *e*, which carries the 30 mass-electrode *d*. Over its entire length, the insulator *b* is provided with an annular hollow space *b*¹, which is closed at all sides and is filled with a non-evaporating, solid but liquidable and heat absorbing cooling medium *f* which during 35 the operation of the internal combustion engine absorbs the heat, fuses and becomes liquid and which, owing to the shocks to which said engine is exposed, moves about within the hollow space *b*¹ in order to cool the insulator. For instance alkali metallic salts, which are liquefiable at the 40 temperature to which the sparking plug is subjected, are adapted for use as heat absorbing cooling media, the temperature of evaporation of said salts being higher than the temperature to which the sparking plug ever is subjected. Further convenient cooling media are for instance metallic sodium, metallic lithium, metallic potassium and substances of like characteristic.

Preferably in order to increase the cooling effect of the plug, the hollow space *b*¹ of the plug-casing *e* also charged with a cooling medium *f* of the kind contained in the hollow space *b*¹ of the insulator *b*.

Compared with the hitherto known sparking plugs, the sparking plug above described is more reliable and has a longer life in view of its special construction for attaining an effective cooling.

What I claim is—

1. A sparking plug comprising in combination, a double-walled hollow insulator which is closed at both ends and thus forms an entirely closed hollow casing with a central passage bounded by the inner wall of said insulator, a central electrode extending through and out of said passage, a plug casing secured to the outside of said insulator, and a mass-electrode fixed to said plug casing.

2. A sparking plug comprising in combination, 15 a double-walled hollow insulator which is closed at both ends and thus forms an entirely closed hollow casing with a central passage bounded by the inner wall of said insulator, a central electrode extending through and out of said passage, 20 a double-walled hollow plug casing secured to said insulator, said plug casing being closed at both ends and thus forms an entirely closed hollow casing with a central passage bounded by the inner wall of said plug casing, and a mass-electrode 25 fixed to said plug casing.

3. A sparking plug comprising in combination, 30 a double-walled hollow insulator which is closed at both ends and thus forms an entirely closed hollow casing with a central passage bounded by the inner wall of said insulator, a heat absorbing cooling medium in said hollow insulator, a central electrode extending through and out of said passage, a plug casing secured to the outside of 35 said insulator, and a mass-electrode fixed to said plug casing.

4. A sparking plug comprising in combination, 40 a double-walled hollow insulator which is closed at both ends and thus forms an entirely closed hollow casing with a central passage bounded by the inner wall of said insulator, a central electrode extending through and out of said passage, a double-walled hollow plug casing secured to said insulator, said plug casing being closed at both ends and thus forms an entirely closed 45 hollow casing with a central passage bounded by the inner wall of said plug casing, a heat absorbing cooling medium in said hollow insulator and in said hollow plug casing, and a mass-electrode fixed to said plug casing.

ANTON GAZDA.
